US0D1061695S

(12) **United States Design Patent** (10) Patent No.: **US D1,061,695 S**
(45) Date of Patent: ** Feb. 11, 2025

(54) **SPECTACLES**

(71) Applicant: **BALENCIAGA**, Paris (FR)

(72) Inventor: **Demna Gvasalia**, Paris (FR)

(**) Term: **15 Years**

(21) Appl. No.: **35/520,600**

(22) Filed: **Mar. 28, 2024**

(80) **Hague Agreement Data**

Int. Filing Date: **Mar. 28, 2024**

Int. Reg. No.: **DM/236336**

Int. Reg. Date: **Mar. 28, 2024**

Int. Reg. Pub. Date: **Apr. 19, 2024**

(30) **Foreign Application Priority Data**

Sep. 29, 2023 (EM) 015035833-0001

(51) **LOC (15) Cl.** **16-06**

(52) **U.S. Cl.**

USPC **D16/314**

(58) **Field of Classification Search**

USPC D16/300, 309, 313-316, 319-323, 325,

D16/326

CPC . G02C 1/04; G02C 1/06; G02C 5/008; G02C

5/14
